UNITED STATES PATENT OFFICE

ALFRED PARTLOW, OF LINCOLN PARK, MICHIGAN, ASSIGNOR TO VORCLONE CORPORATION, OF MILWAUKEE, WISCONSIN, A CORPORATION OF DELAWARE

WASHING-MACHINE CASING

Application filed August 30, 1928. Serial No. 303,065.

This invention relates to casings for washing machines and particularly for washing machines of the laundry type as distinguished from household machines.

5 An object of the invention is to diminish the radiation of heat from a washing machine casing and at the same time to impart great strength to the walls of said casing by forming said walls of a double thickness of 10 sheet metal with a layer of asbestos or any other suitable heat insulation clamped between the two thicknesses.

Another object is to form the upper portions of the end walls of a washing machine 15 casing separately from the lower portions of said walls, and to attach said upper portions to a cover member for the casing so that when said cover member is raised from its position of use openings will be left in 20 the end walls so as to facilitate raising and lowering of a wash-receiving cylinder normally housed within said casing and mounted upon trunnions projecting through the casing end walls.

25 A further object is to provide efficient means for sealing the joint between the body of said casing and the cover member thereof.

Still another object is to form the bottom 30 of a washing machine casing with a longitudinal slot or other suitable opening for the discharge of such sediment or dirt as may settle in the bottom portion of said casing, and to secure to the under face of the casing, a trough or the like to receive the 35 discharge through slot.

A still further object is to so connect the end walls of a washing machine casing to the peripheral wall thereof, as to avoid exposure of the rivets connecting said walls 40 to the liquid contents of the casing.

These and various other objects the invention attains by the construction hereinafter described and illustrated in the accompanying drawings; wherein:

45 Fig. 1 is a view in front elevation and partial vertical section of a washing machine casing improved in accordance with the invention, this view further disclosing a wash-receiving cylinder in its position of 50 use in said casing.

Fig. 2 is an end view of the same.

Fig. 3 is a fragmentary sectional view taken on the line 3-3 of Fig. 2 and showing the composite construction of the casing walls and the manner of joining the peripheral and end walls of the casing. 55

Fig. 4 is a fragmentary section on line 4-4 of Fig. 1 showing primarily a trough carried by the bottom of said casing.

Fig. 5 is a fragmentary section taken upon the line 5-5 of Fig. 2 and disclosing a means for sealing the joint between stationary and moveable portions of an end wall of the casing. 60

Fig. 6 is a fragmentary vertical section taken upon the line 6-6 of Fig. 2 and disclosing a sealing provision surrounding one of the trunnions of the wash-receiving cylinder. 65

Fig. 7 is a perspective detail view of a sealing ring, one of which is carried by each trunnion of the wash-receiving cylinder at its point of passage through the casing wall. 70

In these views the reference character 1 designates the peripheral wall of the main 75 body of a washing machine casing, and 2 the end walls of said body. The upper portion of said casing is formed by a substantial semi-cylindrical cover 3 which is hinged at 4 to the casing wall 1 and rigidly carries segmental upper portions 5 of the casing end walls, having an extent of approximately 90°. When the cover member is raised, as indicated in dash lines in Fig. 2, segmental openings in the upper portions of the end 80 walls 2 are uncovered by the portions 5. 85

Normally housed within the described casing is a wash-receiving cylinder 7 formed preferably of sheet metal and having its peripheral wall perforated, as is common 90 practice. Rigidly connected to the ends of said cylinder and outwardly projecting from said ends is a pair of trunnion shafts 8 which normally project centrally through the casing end walls, as clearly appears in 95 Figs. 1 and 6. The provision of segmental openings in the upper portions of said end walls and the mounting of segmental closures for said openings upon the hinged cover member is for the purpose of avoiding 100

any interference of the end walls with movement of the trunnions 8 when the cylinder 7 is lifted from or lowered into the casing.

5 Because of the splashing of the water in the lower portion of the casing when the machine is operating, it is desirable to establish a substantially liquid-tight seal between the segments 5 and the stationary portions 10 of the casing end walls. For this purpose metal sealing bars 9 are riveted or otherwise rigidly secured to the substantially radial edges of each segment 5, said bars having wedge-shaped margins 10 projecting 10 beyond said edges. Also a pair of metallic sealing bars 11 is rigidly secured to each wall portion 2 of the casing, along the radial edges thereof, and each of said bars is formed with a substantially V-shaped 15 groove proportioned to snugly receive the wedge portion 10 of the complementary bar 9 when the cover member 3, 5 is in closed position.

To liquid-seal the opening through which 20 each trunnion 8 projects, a sealing ring 12 is pressed or otherwise mounted fast upon the trunnion and is formed with a peripheral V-shaped groove 13. In said groove are normally engaged V-shaped edges of the 25 upper and lower halves 14 and 15 of a sealing ring, said halves being respectively riveted or otherwise rigidly secured to the segment 5 and to the wall portion 2. Thus when the cover 3, 5 is in its normal lowered position any escape of water from the cylinder 30 at the joints between the segments 5 and wall portions 2 or around the trunnions 8 is quite positively prevented.

It sometimes happens that the dirt removed from a wash forms considerable sediment in the bottom portion of the casing of the machine which interferes with a complete and proper cleaning of the wash. It is therefore desirable to provide for the continuous removal of sediment as rapidly as it settles into the lower portion of the casing. For this purpose the disclosed construction forms in the bottom of the casing a slot 16 extending preferably the full length of the 40 casing, said slot opening into an elongated trough 17 of arcuate cross-section (best illustrated in Fig. 4) which is riveted or otherwise suitably secured to the casing bottom. Such settling as may enter said 45 trough are adapted to be drawn off through a suitable waste pipe 18 which, if desired, may further be used to drain soiled water from the casing.

A feature of the described construction is 50 the association of heat insulation with the walls of the stationary portion of the casing so as to minimize radiation of heat from said casing when its contents are heated. Thus as is best seen in Figs. 3, 4, and 6, 55 each end portion 2 of the casing comprises

two thicknesses of metal 2^a and 2^b between which is clamped a layer of asbestos or other heat insulation 2^c. Similarly the peripheral wall 1 of the casing body comprises inner and outer thicknesses of metal 1^a and 1^b and heat insulation 1^c between said thicknesses. Wherever the walls 2 or 1 terminate in a free edge, the asbestos layer 2^c or 1^c is replaced by a strip of metal 19, through which are passed the rivets which clamp together the parts of the composite wall. Thus the asbestos layer is hermetically sealed between the two metallic thicknesses of the casing walls so that it is not subject to deterioration.

70 In connecting the end wall portions 2 to the peripheral wall 1 it is preferred to outwardly flange the peripheral margins of the wall members 2 as indicated at 21, the flanges 21 being fitted into the ends of the partial cylinder formed by the wall 1 and being riveted as indicated at 22 or otherwise suitably rigidly attached to said end portions.

75 A washing machine casing constructed as 80 above described greatly increases the length of time during which the liquid contents of a washing machine may be maintained at a working temperature. The continuous discharge of dirt and sediment into the trough 85 17 as fast as it settles to the bottom of the casing permits of a complete and thorough cleaning of the wash regardless of how badly it may have been initially soiled. Also the described provision of segmental 90 members upon the cover of the casing for normally closing openings in the upper parts of the casing end walls permits the wash-receiving cylinder to be either completely or 95 partially removed from the described casing 10 for the purpose of dumping the contents of said cylinder.

11 While it is apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

11 What I claim is:

1. In a washing machine, the combination with a wash-receiving cylinder having trunnions outwardly projecting from its ends, of a circumferentially continuous sealing ring snugly engaging each trunnion, an open-topped cylindrical casing normally receiving said cylinder, and having a removable cover for its top opening, the end walls of said casing being formed with openings in their upper portions, extending from said top opening substantially to the casing axis, said cover comprising closures for the casing end wall openings, said closures and the casing end walls being formed jointly with 11

apertures at their meeting edges to receive said trunnion, in the closed position of the cover, means carried by the casing end walls and said closures at the edges of said aperture for water sealing engagement with said rings, and means establishing a water-seal between the meeting edges of the casing end walls and said closures in the closed position of the cover.

5 2. An open topped sheet-metal cylindrical casing having a cover removably engageable with its top opening, the casing and its cover each having end walls, meeting edge to edge in the applied position of said cover, and sealing strips carried by said end walls upon their meeting edges, the strips on certain of said edges being grooved to snugly receive the strips on the opposing edges.

10 3. In a device of the character described, the combination with an open-topped casing having a cover removably applicable to its top opening, the casing and its cover each having end walls meeting edge to edge in the applied position of the cover, and being 15 jointly formed at their meeting edges with circular openings, a container disposed in said casing and removable through its top opening and having trunnions accommodated by said circular openings, when the 20 container is in the casing, a sealing ring carried by each trunnion, and sealing members carried by the edges of said circular openings adapted for interfitting sealing engagement with said rings.

25 35 In testimony whereof I sign this specification.

ALFRED PARTLOW.
